(57) **CLAIM**

The ornamental design for a control device for liquid distribution equipment, as shown and described.

DESCRIPTION

FIG. 1 is a perspective view of a control device for liquid distribution equipment;

FIG. 2 is a top view thereof;

FIG. 3 is a front elevation view thereof;

FIG. 4 is a right side elevation view thereof;

FIG. 5 is a left side elevation view thereof; and,

FIG. 6 is a bottom view thereof.

The rear side opposite the front side is flat and unornamented.
